(57) **CLAIM**

The ornamental design for an ultrafine bubble generating stirring ball, as shown and described.

DESCRIPTION

FIG. 1 is a perspective view of an ultrafine bubble generating stirring ball, showing my new design;
FIG. 2 is another perspective view thereof;
FIG. 3 is a front view thereof, the rear, the left side, and the right side being identical images of the front;
FIG. 4 is a bottom view thereof, the top being an identical image of the bottom; and,
FIG. 5 is a perspective view of the ultrafine bubble generating stirring ball in a container.

The broken lines of FIGS. 1, 2 & 5 illustrate portions of the ultrafine bubble generating stirring ball, additional ultrafine bubble generating stirring ball, and the container which all form no part of the claimed design.
